UNITED STATES PATENT OFFICE.

MAHLON A. SIDWELL, OF LOS ANGELES, CALIFORNIA.

REVERSING MACHINE.

1,421,104.

Specification of Letters Patent. Patented June 27, 1922.

Application filed December 14, 1920. Serial No. 430,793.

To all whom it may concern:

Be it known that I, MAHLON A. SIDWELL, a citizen of the United States, residing at Los Angeles, in the county of Los Angeles and State of California, have invented a new and useful Reversing Machine, of which the following is a specification.

My invention has special reference to mechanism more especially designed for use 10 as a means for holding sacks or bags whereby they may be readily reversed; that is, turned inside out for cleaning purposes, removing any remnant of the stuffing or other contents that may have been contained there- 15 in and which tends to adhere to the inner side of the bags, sacks or other similar article.

My invention is more particularly adapted 20 for the purpose of turning toy animals, dolls, pin cushions and other like articles which have to be turned right side out after being stitched upon a sewing machine.

Primarily, my invention seeks to provide 25 a means of the character stated adapted for conveniently and expeditiously facilitating the turning of the toy body or other like fabric body arranged for being stuffed with saw dust or other like filling and which is of an inexpensive, simple and compact arrangement, onto which the object to be turned 30 may be easily adjusted and clamped and in such manner that the operation of turning or reversing the bag or other hollow object can be instantly accomplished by the operator 35 and the said object, when turned, quickly removed or disconnected from the holding means.

With other minor objects in view that will 40 hereinafter be apparent, my invention consists of a reversing means that embodies the peculiar features of construction and novel combination of parts, fully stated in the following detailed description, specifically mentioned in the claim and illustrated in the ac- 45 companying drawings, in which:

Figure 1 is a perspective view of my improved construction of reversing machine, the movable article clamping devices being shown at their elevated or clamped position.

50 Figure 2 is a side elevation of the movable clamping member and its actuating means, the same being shown at the lower or clamping position.

Figure 3 is a detail vertical section of the

expansible connecting element of the movable clamping means hereinafter fully explained.

Figure 4 is a detail cross section of the table, the fixedly held clamping member, the vertical shifttable connection and the guides 60 therefor and the table frame.

In the practical embodiment of my invention the same consists of a table to which is fixed an upright stationary clamping member. The table is also provided with vertical 65 bearings to sustain a vertically movable frame that is mounted in such bearings. This frame carries a clamping member which is adapted to be brought down and engage the stationary clamping member so as to grip 70 the bottom of the article to be turned between the opposing parts of the clamping members. The parts are so arranged and designed that the operator can conveniently 75 place the article to be turned over the lower end of the upper or movable clamping member and, by foot pressure, bring the movable clamping member down to grip the article between it and the stationary clamping member, the operator meanwhile grasping 80 the outer or open end of the article which, when the clamping members are together, he turns down over the stationary clamping members and thereby reverses the object— 85 without the use of special tools or without the necessity of making hand adjustments of any of the parts of the mechanism.

Referring to the details of construction, 1 designates the hollow tube, which is hereinafter termed the upper movable clamping member, and this tube has a coupling head 7 which screws onto a slightly larger tube 13, the diameter of the said tube 1 varying according to the work to be done but always 95 with a corresponding change in the diameter of the opposing rod 2, with which it cooperates.

The rod 2 has an enlarged base provided 100 with a threaded shank 8 for fitting a screw socket 80 in the table 18, and the said rod 2, in practice, may be of various lengths corresponding with the distance that the tube 13 extends from the tube 14, presently again referred to.

4 indicates a standard which is bolted to the table top and it includes a bearing 3 in which is slidably secured the tube 14 before

referred to, and which constitutes a standard in which the end 13^a of the U-shaped member is adjustably mounted.

The lower end of the standard tube 14 passes through a guide 12 in the table 18 and is joined, by a coupling 9, with a bent tube 15, that includes a pendent portion 15^a which slidably engages the bearing 10 bolted onto the inner face of a cross member 21 of the table frame, which includes opposite standards 16—16 and 23—23, braces 17—17 and a bottom cross bearing 22.

The lower end of the part 15^a of the bent member 15, terminates in a foot pedal 11 for conveniently pulling down the movable or upper clamping member, if desired.

24 designates a stout coil spring that fits around the upper end of the standard 14, which has one end resting on the bearing 3 and the other end engaging a collar 5 adjustably mounted on the said standard, as is clearly shown in Figure 3.

Arranging the parts that constitute my reversing machine, as shown and described, the operation thereof will be readily apparent to those familiar with the handling of bag turning mechanism, in which devices are provided for holding the bag or other fabric object to be turned.

In my construction, the object to be turned is slipped up over the hollow tube which is positioned as indicated in full lines on Figure 1. The foot of the operator is then placed on the pedal 11 which, when pressed down, through the connections 15, 14 and 13, depresses the movable parts to the position shown in Figure 2, with the lower end of the tubular member 1 abutting the bottom of the object and clamping such object bottom down onto the bulbular end of the stationary member 2, thereby holding the object firmly between the said bulbular end 20 and the end 19 of the member 1.

The operator then grasps the open edges 45 around the mouth of the object, pulls the said mouth down over the rod 2 and thereby reverses the said object, by turning it inside out.

Foot pressure is then removed from the 50 pedal 11, which allows the upper or movable part of the machine to automatically, under action of the spring 24, return to the uppermost or normal position. The turned object is then removed from the member 2 and the 55 process of reversing is repeated on another like object.

With my construction of reversing means, the operation of gripping the object to be

turned and turning it inside out can be quickly, conveniently and satisfactorily accomplished without the need of adjusting or specially setting any of the clamping or object holding parts, after the object has been turned, as stated, since all that is necessary is to release the foot pressure, which allows for the separation of the opposing clamping elements 1 and 2 and thereby provides sufficient space between the said elements for withdrawing the turned object from between them.

While the special arrangement of the parts as shown and hereinbefore described presents a practical development of my invention, it will be understood that I do not limit myself to the precise arrangement of the parts shown, since the said parts may be readily modified and varied to suit the particular work desired to be done, without departing from the broad features of my invention as comes within the scope of the appended claim.

What I claim is:

In a reversing machine for the purposes described, the combination with a supporting frame, including leg members and a 85 table top mounted thereon, and a standard secured to and extended vertically from one end of the table top and including a vertically apertured bearing; a clamping post fixedly connected to and projected vertically 90 above the table, a plunger frame which includes a vertical member slidably engaging the apertured bearing of the standard and movable through the table, an extension secured to the lower end of the said vertical 95 member, the said extension including a foot lever equipped pendent member, a guide on the table supports in which the foot lever equipped pendent extension is slidably 100 mounted, a spring device engaging the vertically slidable member and the apertured bearing in which the said bearing is mounted, whereby to normally force the said vertical member upwardly, when pressure on the foot lever is released, and an inverted 105 U-shaped frame adjustably attached to the said vertically shiftable member and a clamp member attached to the inverted U-shaped frame and supported for being brought 110 down into contact with the stationary clamping member, when pressure is applied to the foot lever, whereby to clamp the article to be held between it and the said opposing fixedly held clamp.

MAHLON A. SIDWELL.
